LUBRICATING DEVICE

John P. Laux, Bethlehem, Pa., and Eben Ray
Packer, New Rochelle, N. Y.

Application June 13, 1933, Serial No. 675,544

5 Claims. (Cl. 184—27)

The present improvements relate to the lubrication of the operating cylinders and air pump mechanism of locomotives and has for its object to provide an improved means therefor adapted for inexpensive application to standard installations and to be operative automatically to effect lubrication of the air pump mechanism responsive to the operation thereof and independent of the movement of the locomotive itself.

10. In accordance with the present invention, a mechanical type of force feed lubricator is desirably employed to deliver a measured quantity of the oil or lubricant to the steam line of the air pump operating cylinder to effect its proper 15 lubrication and the actuation of the mechanical lubricating device is effected by motion transmitted from the piston rod of the air pump mechanism through the instrumentality of a frictional or floating connector fitted upon the piston rod 20 which may preferably be in the form of a swab holder adapted for the lubrication of the rod. This simplified arrangement, in addition to affording of particularly inexpensive installation to standard air pump construction without expensive alterations thereof, provides for improved 25 automatic lubrication in that the lubricant is delivered or fed proportionate to the operation of the air pump and for the full period of its operation and then only. In this latter respect 30 it presents important advantages over types of automatic oilers as heretofore used wherein the oil feeding devices are connected to operate only when the locomotive is moving, which, in addition to lubricating when not required with waste 35 of oil, results in objectionable and destructive wear and noise from lack of lubrication during the often occurring, extended periods of pump operation to maintain the air pressure when the locomotive is at rest.

40. The foregoing and other important features and advantages of our present improvements will be more fully understood by reference to the accompanying drawing wherein like reference characters are applied to the corresponding parts 45 in the several views.

In the drawing:

Fig. 1 is a diagrammatic view in side elevation showing our improved lubricating device as applied to the air pump mechanism of a locomotive. 50. Fig. 2 is a detail view showing the improved connector arrangement in plan.

Fig. 3 is a partial view in vertical section showing a conventional type of force feed pump lubricator.

55. In the approved embodiment of our invention

as herein shown, 1 indicates the steam cylinder of the fluid motor of the air pump mechanism within which operates the usual piston having connected thereto the piston rod 3 extended downwardly within the pump cylinder 4 where- 60 in it is provided with the air pump piston in accordance with the usual construction. At 5 there is shown the usual steam line connected by conduit 6 to the intake port 8 of the cylinder 1 having the usual exhaust port 9 and exhaust 65 pipe 7.

Associated with this conventional arrangement, there is provided a pressure feed lubricating device of the mechanically actuated type indicated at 10 and provided with a movable actuating arm 70 12 mounted upon an actuator shaft 13. The delivery port of the lubricator 10 is connected by tube or pipe 14 to the steam line 5 and is provided with a check valve 15 adjustable to regulate the feed of the oil as required for proper 75 lubrication.

The simplified and improved means for operating the lubricating device, as shown, comprises a connector member *c* composed of ring segments 15—16 fitted upon the piston rod 3 to have frictional securing engagement therewith, one of the segments having an arm extension 18 connected by a link 19 to the actuating arm 12 of the oil feed device 10 by means of pivot connections 20—21 as shown. The ring segments, as illus- 80 trated, are formed with radial extensions or ears which are formed with apertures to receive the clamping bolts 22 loosely fitted therein and provided with washers 23 and nuts 24 threaded on the bolts to adjust the tension of coil springs 25 85 interposed between the ear portions and the washers to exert a constant pressure of the ring upon the piston rod. In accordance with a further feature of the invention, the connector ring member has fitted therein the customarily em- 90 ployed swab 26 which may be of cotton fabric, impregnated with lubricating grease for lubrication of the piston rod.

In operation, as will be readily understood, the frictional grip of the connector on the piston rod 100 is sufficient to effect the actuation of the arm 12 of the lubricator to feed the lubricant. As the stroke of the piston rod is greater than the allowable distance of travel of the connector, as determined by the spacing of the lower gland 27 105 of the steam cylinder and the gland 28 of the pump cylinder, the frictional grip of the connector will be slipped at the end of its stroke in each direction upon its engagement with the glands.

As will be appreciated, any suitable mechanical feed lubricating device may be employed, there being here shown a simplified form consisting of a block 30 positioned within the lubricator 5 casing and having a vertical bore 31 to receive the feed plunger 32. Communicating with the bore 31 is an oil intake port 34 and out duct 35 having a vertical discharge duct 36 connected therewith and provided with a seat for a ball 10 check 37. The oil feed pipe is connected to the discharge duct as shown. For operating the feed plunger 32, the actuating shaft is formed with an eccentric portion 38 upon which is fitted a collar 39 connected by pivotal link 40 to the 15 plunger 32 whereby upon oscillation of the actuator shaft 13 the plunger will reciprocate vertically with a short stroke, sufficient to entrap and feed a minute quantity of oil at each stroke.

While a single feed from the lubricant feed 20 device is shown, it will be understood that a multiple feed device may be similarly operated for lubricating other parts, such as the cylinders of compound air compressor arrangements, both steam and air. Likewise, as shown in dotted lines 25 in Fig. 2, a flexible connection 42 may be provided from the feed device to the connector ring for delivering oil to the swab for the automatic lubrication thereof.

While we have shown and described an 30 approved embodiment of the features of our improvements it will be understood that various modifications may be made therein without departing from the scope of the invention as defined in the appended claims.

35 Having described our invention, we claim:

1. A lubricating device for air pump mechanisms of locomotives having in combination with the fluid operating motor, air pump and piston rod associated therewith, a lubricant feed device 40 provided with an actuator shaft and an arm for moving said shaft, operating means therefor comprising a connector member slidably fitted to the piston rod to be movable therewith for part of the piston rod stroke and connections from said 45 connector member to the arm to transmit motion thereto to actuate the feed device.

2. A lubricating device for air pump mechanisms of locomotives having in combination with the fluid operating motor, air pump and piston 50 rod associated therewith, a lubricant feed device provided with an actuator shaft and an arm for moving said shaft, operating means therefor comprising a connector member fitted to the piston

rod to have slidable frictional engagement therewith, connections from said connector member to the arm to transmit motion thereto to actuate the feed device and said connector including a swab positioned in engagement with the rod, substantially as described. 80

3. A lubricating device for air pump mechanisms of locomotives having in combination with the fluid operating motor, air pump and piston rod associated therewith, a lubricant feed device 85 provided with an actuator shaft and an arm for moving said shaft, operating means therefor comprising a connector member composed of ring segments fitted to surround the piston rod, means for resiliently clamping the segments to the rod 90 and connections from the connector member to the arm to transmit motion from the piston rod thereto.

4. A lubricating device for air pump mechanisms of locomotives having in combination with the fluid operating motor, air pump and piston rod associated therewith, a lubricant feed device provided with an actuator shaft and an arm for moving said shaft, operating means therefor comprising a connector member composed of ring 95 segments fitted to surround the piston rod, a swab interposed between the segments and the rod, said ring segments having perforated ear portions, clamping bolts fitted within the perforations, nuts threaded to said bolts with springs 105 interposed between the segment and the nuts and connections from the connector member to the arm to transmit motion from the piston rod thereto.

5. A lubricating device for air pump mechanisms of locomotives having in combination with the fluid operating motor, air pump and piston rod associated therewith, a lubricant feed device provided with an actuator shaft and an arm for moving said shaft, operating means therefor 110 comprising a connector member composed of ring segments fitted to surround the piston rod, one of said segments having an arm extension, a swab interposed between the segments and the rod, means for resiliently clamping the segments into 115 frictional engagement with the piston rod, connections from the segment extension arm to the actuator arm to transmit motion from the piston rod thereto and a lubricant feed pipe from the feed device to the fluid intake of the operating 125 motor, substantially as described.
